BANK FIXTURE

Filed Nov. 10, 1924

Fig. 1

UNITED STATES PATENT OFFICE.

CHARLES A. HONSINGER, OF DETROIT, MICHIGAN.

BANK FIXTURE.

Application filed November 10, 1924. Serial No. 749,092.

To all whom it may concern:

Be it known that I, CHARLES A. HONSINGER, a citizen of the United States, residing at Detroit, in the county of Wayne 5 and State of Michigan, have invented certain new and useful Improvements in Bank Fixtures, of which the following is a specification, reference being had therein to the accompanying drawings.

10 In my Patent No. 1,460,584, dated July 3, 1923, there is disclosed a bank safety device for window and counter construction, the device being in the form of a deal plate or structure which will permit of money and 15 valuables being handed back and forth from one side of the bank counter to the other without any danger of money being unlawfully obtained by a person on the outer side of the counter slipping the hand over the 20 counter without detection.

This invention involves the use of a deal plate, such as mentioned above, in combination with a novel bandit proof wicket or counter fixture, the fixture being bullet proof 25 and affording absolute protection to bank officials in the event of robbery. Without detracting from the artistic appearance or finish of bank fixtures, my counter fixtures prevents the bandit or unauthorized person 30 from scaling or climbing over the top of the counter fixture and while the fixture is bullet proof, yet it does not interfere with any conversation between persons on opposite sides of the counter fixture. Provision is 35 made for the passage back and forth of parcels too large to pass through the deal plate, and provision is also made whereby a bank official may safely manipulate a fire arm against intruders should it become necessary.

40 My counter fixture will be hereinafter specifically described and then claimed, and reference will now be had to the drawing, wherein—

Figure 1 is a perspective view of the inner 45 side of the counter fixture;

Fig. 2 is a vertical sectional view of the same, and

Fig. 3 is a similar view, on a larger scale of a gun loop hole and closure therefor.

50 In the drawing, the reference numeral 1 denotes a counter such as may be used in a bank or similar institution, and forming part of the counter is a deal plate 2 having a longitudinal partition 3 and a transverse 55 partition 4 with the partition 3 providing

two "one-way" passages 5 and it is by virtue of these passageways that the bank teller may safely pass out money to a customer or the customer pass in money to the teller.

Over this deal plate and on the counter 60 1 is erected a metallic fixture or partition 6 having a multiplicity of panels 7, 8 and 9. The panels 7, adjacent the teller's position at the counter 1, are preferably made of bullet proof glass and metallic plates, a 65 bullet proof glass being used in such panels where it is necessary for the teller and customer to observe each other.

The panel 9 is preferably in the form of a hinged door, made of bullet proof glass 70 or metal and this hinged door is located above the deal plate so that bulky matter may be passed back and forth through the fixture, and in some instances the hinged door or panel may be dispensed with and a 75 fixed panel substituted therefor.

The panel 8 is located above the panel 9 and is preferably an apertured metallic plate or bullet proof wicket, the apertures or interstices of the wicket permitting of a 80 conversation being carried on between the teller and depositor. This panel is provided with a loop hole 12 normally closed by an outwardly opening closure 13, which when closed, has its outer face flush with the outer 85 face of the panel, whereby it cannot be conveniently opened from the outer side of the panel 8. The closure 13 is hingedly mounted, as at 14, on the plate 15 secured to the inner wall of the panel 8, and on the inner 90 wall of the closure 13 is a concave presser plate 16 against which the muzzle of a gun may be placed to force the closure 13 open, the muzzle of the gun slipping off of the plate 16 and outwardly whereby the barrel 95 of the gun will be held between the panel 8 and the closure 13. The manipulator of the gun may observe intruders through the apertured plate or wicket 8 and may use the gun to either injure or capture intruders.

100 A spring 17 may be used with the plates 15 and 16 to hold the closure 13 normally closed, yet permitting said closure to yield openly under gun pressure.

The fixture or partition 6 has a top rail 105 18 provided with upstanding sharp guards 19 and outstanding sharp guards 20, the guards 19 and 20 providing a fender or entanglement that will prevent intruders from quickly scaling the fixture or partition, con- 110

sequently there is another degree of safety for the teller and other employees of the bank.

The panels 7, made of bullet proof glass or metal, may also support outwardly opening closures 21 for loop holes in the panels, the closures being similar to that used in connection with the apertured panel 8. As a matter of fact any bank protection or fixture may be provided with normally closed loop holes so that a bank official may use a gun when occasion so requires.

What I claim is:—

A bank fixture including a partition having a loophole, an outwardly opening closure for said loophole, a gun engaging means on the inner side wall of said closure adapted under gun pressure to cause said closure to start opening before the gun is within the loophole, and means holding said closure normally in a closed position. 15 20

In testimony whereof I affix my signature.

CHARLES A. HONSINGER.
